UNITED STATES PATENT OFFICE.

WILLIAM H. LEWIS AND JOHN A. PILCHER, OF ROANOKE, VIRGINIA.

SIX-WHEEL TRUCK FOR RAILWAY-CARS

1,095,582.

Specification of Letters Patent.

Patented May 5, 1914.

Application filed August 28, 1913. Serial No. 787,148.

To all whom it may concern:

Be it known that we, WILLIAM H. LEWIS and JOHN A. PILCHER, citizens of the United States, residing at Roanoke, in the county of Roanoke and State of Virginia, have invented certain new and useful Improvements in Six-Wheel Trucks for Railway-Cars, of which the following is a specification.

10 This invention relates to six-wheel trucks for railway cars and its object is to provide a simple and substantial means of equalization of the weight among the three pairs of wheels of the truck.

15 In the six-wheel truck of our previous Patent No. 1,054,697, March 4, 1913, it was necessary that the centers of the groups of springs come at a point approximately two-thirds of the distance between the middle 20 axle and the outer ones. This fixed location in some instances is a handicap to economical construction and in other instances it is almost imperative that the springs be located midway between the several axles.

25 In this invention we are enabled to secure this advantage without the intervention of additional equalizing bars below or above the side frames and without the use of a pivotal journal box for the middle axle as is used in some types of six-wheel trucks. At 30 the same time we obtain perfect equalization of the weight among the three pairs of wheels.

35 The particular object, therefore, of this invention is to provide the truck of our previous invention with means for overcoming this disadvantage, with which object in view it consists in the combination of parts as will be hereinafter described and finally claimed.

40 In the drawings, Figure 1 represents a plan view of the truck of our invention and Fig. 2 a side elevation of the same. Fig. 3 shows, in side elevation, a modified arrangement of the equalizing side frames of our invention. Figs. 4 and 5 show in plan view and side elevation respectively a still further modified form of the truck of our invention in which the wheels are not equally spaced.

45 Referring now to the drawings in which like parts are similarly designated wherever they occur, 1 represents the outer truck wheels at one end of the truck, 2 the middle wheels and 3 the outer wheels at the other end of

the truck, on their respective axles, 4, 5, and 6. These axles are journaled in the customary journal boxes 7, 8 and 9.

50 The weight of the car body rests on the center plate 10 of a truck bolster 11. This truck bolster 11 may be of any convenient design, having two arms 12 adapted to transfer the load to one end of the truck and two arms 12^a, adapted to transfer the load to the other end of the truck, the arms being 55 preferably disposed between the wheels. The arms 12 and 12^a preferably extend through openings 13 and 13^a in two pair of articulated side frames 14 and 15 and are guided in these openings by means of vertically disposed guides 16. Between the arms of the truck bolster and the articulated side frames are interposed the truck springs 17 and 17^a. To the end of each side frame 14 is secured, by means of the bolts 18 and 70 the tie bar 20, a journal box for the outer axle 4, and to the inner end of each of these side frames is secured, by means of the bolts 19 and tie bar 21, a journal box for the middle axle 5. To the outer end of each side 75 frame 15 is secured, by means of the bolts 22 and the tie bar 23, a journal box for the other outer axle 6. The inner end 24^a of the side frame 15, however, passes over, under, or to the side of the side frame 14 80 and at 24 it is pivotally supported by the side frame 14. Hence the side frame 14 is, in effect, a rigid side frame and the side frame 15 a trailing side frame.

85 The point of support 24 may be either 90 over the bolster opening or below it and the joint may be of any construction that will allow the free movement of the frame 15 relative to the frame 14. In some instances also, it may be desirable to rest the inner 95 end of the frame 15 directly on the bolster arm 12 where it passes through the frame 14. In this case, of course it would be necessary to use heavier springs in the frame 14 than in the frame 15.

100 The equalization of the weight on the three pairs of wheels is effected as follows: The load from the car coming on the bolster 11 is divided, a part of it being transferred to the side frames 14 and a part to the side 105 frames 15. The part of the bolster load coming on the side frames 14 is distributed directly to the axles 4 and 5 through the side frames 14 in such proportions as will be determined by the location of the point 110

of application of this load to the frames 14. The part of the bolster load coming on the side frames 15 is also divided, a portion going directly to the axle 6 and the remainder to the side frames 14 through the inner end 24^a of the frame 15, it being applied to the frames 14 at the point 24. The portion of the load of the side frames 15 that comes on the frames 14 at 24 is divided between the axles 4 and 5. The proportion of the load from the side frame 15 going to the axle 6 and to the side frames 14 will likewise be determined by the location of the point of application of the bolster load to the frames 15. In trucks where the wheels are equally spaced and the truck center plate is located immediately over the middle axle, the bolster load may be applied to the side frames 14 and 15 at any points along the frames, provided that the points of application to the two frames are symmetrical about the vertical center line of the middle axle and provided further that the horizontal distance from the point of its application to the frame 15 to the point 24 where the end of the frame 15 is supported by the frame 14 be made equal to twice the horizontal distance from this point of its application to the vertical center line of the axle 6. If these conditions be fulfilled the loads will be perfectly equalized among the three axles.

In Figs. 1 and 2 the bolster arms 12 and 12^a are shown as disposed midway between the axles and the point 24 as being immediately over the point of application of the load from the bolster arms 12. This satisfies the conditions just stated and the load will be equalized as desired.

In Fig. 3 the bolster arms 12 and 12^a are shown nearer the axles 4 and 6 than the middle axle 5 but symmetrical about the vertical center line of the axle 5. The distance from the point of application of the load from the bolster arms 12^a to the center of the axle 6 is one-half of the distance from this point to the point 24. Hence the conditions are fulfilled in this case and the loads will be equalized.

In Figs. 4 and 5 is shown a truck of this type in which the wheels are unequally spaced and in which the center plate load is applied to one side of the vertical center line of the middle axle.

In each of these trucks the equalization is obtained in practically the same manner, by correctly proportioning the lengths of the various parts.

From this it is evident that those skilled in the art might make various changes in the detail design of our invention without departing from the essential features thereof.

Having thus described our invention what we claim is,

1. In a six-wheel truck for railway cars,

the combination of a bolster having outwardly extending arms, rigid side frames having secured thereto the journal boxes for an outer and for the middle axle, and trailing side frames pivotally connected to the said rigid side frames and having secured thereto the journal boxes for the other outer axle, substantially as described.

2. In a six-wheel truck for railway cars, the combination of a bolster having outwardly extending arms, rigid side frames having secured thereto the journal boxes for an outer and for the middle axle, and trailing side frames pivotally connected to the said rigid side frames at a point removed from the middle axle, said trailing side frames having secured thereto the journal boxes for the other outer axle, substantially as described.

3. In a six-wheel truck for railway cars, a pair of articulated side frames in combination with a bolster having outwardly extending arms, said articulated side frames being adapted to receive the load from the said bolster arms and equalize it among the truck axles, one of the pair of said articulated side frames being further adapted to receive journal boxes for one of the outer and for the middle axle and the other of the pair of said articulated side frames being further adapted to receive a journal box for the other of the outer axles, substantially as described.

4. In a six wheel truck for railway cars, a pair of articulated side frames in combination with a bolster having outwardly extending arms at each end, one of the said pair of articulated side frames being adapted to receive the load from one of the said bolster arms and distribute it between the outer truck axle and the middle truck axle, the other of the said pair of articulated side frames being adapted to receive the load from one of the said bolster arms at the opposite end of the truck and distribute it between the other outer truck axle and the first of the said pair of said frames, substantially as described.

5. In a six-wheel truck for railway cars, a pair of articulated side frames in combination with a bolster having outwardly extending arms at each end, one of the said pair of articulated side frames being adapted to receive the load from one of the said bolster arms and distribute it between the outer truck axle and the middle truck axle, the other of the said pair of articulated side frames being adapted to receive the load from one of the said bolster arms at the opposite end of the truck and distribute it between the other outer truck axle and the first of the said pair of articulated side frames, the said pair of articulated side frames being further adapted to equalize the loads from the said bolster arms among the

three truck axles without the intervention of additional equalizer bars or pivotal journal boxes, substantially as described.

6. In a six-wheel truck for railway cars, 5 a pair of articulated side frames in combination with a bolster having outwardly extending arms at each end, the first of the said pair of articulated side frames being adapted to receive journal boxes for an 10 outer truck axle and for the middle truck axle, the second of the said pair of articulated side frames being adapted to receive a journal box for the other outer truck axle, the first of the said pair of articulated side frames being further adapted to receive the load from one of the said bolster arms and distribute it between an outer axle and the middle axle, and the second of the 15 said pair of articulated side frames being further adapted to receive the load from another of the said bolster arms and distribute it between the other outer axle and the first of the said pair of articulated side frames, substantially as described.

25 7. In a six-wheel truck for railway cars, a pair of articulated side frames in combination with a bolster having two outwardly extending arms at each end, each of said arms being adapted to support one-fourth 30 of the load of said bolster, one of the said articulated side frames being adapted to receive the load from one of the said bolster arms and deliver it to an outer axle and to the middle axle, and the second of said side 35 frames being adapted to receive the load from one of the said bolster arms at the opposite end of the truck and deliver two-thirds of said load to the other outer axle and the other one-third of said load to the 40 first of said side frames at such a point longitudinally of the said side frame that its distribution to the first two axles will supplement the loads delivered thereto by the first bolster arm to equalize the load on all 45 the axles, substantially as described.

50 8. In a six-wheel truck for railways cars, the combination of a bolster having two outwardly extending arms at each end, side frames at each side of the truck adapted to receive the load from the two of said bolster arms at one end of the truck, said side frames being further adapted at their outer ends to receive the journal boxes for the one end axle, and at their inner ends to receive the journal boxes for the middle axle, and trailing side frames at each side of the truck adapted to receive the load from the two of said bolster arms at the opposite end of the truck, said trailing side frames

being further adapted at their outer ends 60 to receive the journal boxes for the other outer axle, the side frames on each side of the truck having articulated motion relative to each other, the point of articulation being removed from the middle axle, substantially 65 as described.

9. In a six-wheel truck for railway cars, the combination of a bolster having two outwardly extending arms at each end, rigid side frames at each side of the truck adapted to receive the load from the two of said bolster arms at one end of the truck, said rigid side frames being further adapted at their outer ends to receive the journal boxes for one of the outer axles, and at their inner ends to receive the journal boxes for the middle axle, and trailing side frames at each side of the truck adapted to receive the load from the two of said bolster arms at the opposite end of the truck, said trailing 75 side frames being further adapted at their outer ends to receive the journal boxes for the other outer axle, the said trailing side frames being further adapted at their inner ends to be supported by the said rigid side 80 frames, substantially as described.

10. In a six-wheel truck for railway cars the combination of a bolster having two outwardly extending arms at each side disposed symmetrically about the middle axle, rigid 90 side frames adapted at their outer ends to receive the journal boxes for one of the outer axles and at their inner ends to receive the journal boxes for the middle axle, and trailing side frames adapted at their outer ends to receive the journal boxes for the other outer axle and adapted at their inner ends to be supported by the said rigid 95 side frames, each of said side frames being further adapted to support one of the said 100 outwardly extending bolster arms and equalize the load thereof among the three axles, the point of support of the said outwardly extending bolster arms on the said trailing side frames being at one-third of the horizontal 105 distance from the vertical center line of the outer axle in said trailing side frame to the vertical line passing through the point of support of the said trailing side frames on the said rigid side frames, substantially as 110 described.
